Primary Examiner — Clare E Heflin(74) *Attorney, Agent, or Firm* — Nixon & Vanderhye, P.C.(57) **CLAIM**

The ornamental design for "ceiling light," as shown and described.

DESCRIPTION

FIG. 1 is a perspective view of a ceiling light in accordance with my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof, the left-side elevational view being identical thereto; and,

FIG. 7 is a section taken along the line 7-7 of FIG. 4.

The broken lines shown on the drawings depict portions of the ceiling light that form no part of the claimed design.
